Atlys.

UNITED STATES PATENT OFFICE.

CHARLES E. GIERDING, OF MANSFIELD, OHIO, ASSIGNOR TO THE OHIO BRASS COMPANY,
OF MANSFIELD, OHIO, A CORPORATION OF NEW JERSEY.

TROLLEY-BASE.

1,131,831.

Specification of Letters Patent.

Patented Mar. 16, 1915.

Original application filed March 5, 1913, Serial No. 752,043. Divided and this application filed March 19, 1914. Serial No. 825,745.

To all whom it may concern:

Be it known that I, CHARLES E. GIERDING, a citizen of the United States, residing at Mansfield, in the county of Richland and 5 State of Ohio, have invented certain new and useful Improvements in Trolley-Bases, of which the following is a true, clear, and exact specification.

My invention relates to trolley bases of 10 the type which are generally used upon electric cars and has more particular reference to improvements in trolley bases of this character which will render it convenient and easy to remove and replace or interchange trolley bases in case of damage 15 and repairs and the like.

One of the objects of my invention is to 20 provide an improved device of this character which will be simple, durable, and reliable in construction and effective and efficient in operation.

Other objects of my invention will appear hereinafter.

Referring to the accompanying drawings, 25 Figure 1 illustrates partly in section a trolley base embodying my invention. Fig. 2 is a horizontal sectional view on the line 2—2 of Fig. 1, and Fig. 3 is a bottom plan view of the base plate and locking device.

30 In the accompanying drawings I have illustrated my invention as embodied in a structure which in practice I have found best adaptable to various conditions and requirements such as manufacturing and operating conditions, but it will be obvious to 35 one skilled in the art, after having obtained an understanding of my invention from the disclosures herein made, that my invention is equally as capable of embodiment in other 40 structures without departing from the scope and spirit thereof.

The structure shown in the drawings is 45 of the type which is adapted for mounting upon the roof of the car and for maintaining the trolley in yielding relation to the trolley pole under such variations and conditions as are usually found in practice. This structure has a broad, flat base plate or member A provided with a number of 50 bolt holes A¹, preferably at the corners of said plate, permitting the base plate to be securely fastened to the top of the car. Rising vertically from this base and preferably formed integral therewith is a hollow 55 turret post or standard B, which is

circular in section and which serves as a central supporting member around which the several operating parts rotate in adapting themselves to the movements of the car relatively to the trolley wire. A hollow, inverted member C, which is also preferably circular in section, forms a turret or rotary member mounted to rotate upon the upstanding post or standard B. Suitable bearings, such as the vertically disposed roller bearings D, are interposed between the inner wall of the turret C and the periphery of the post B to reduce the friction incident to the rotary action of the turret. The structure which I have illustrated in the drawing is of the type constituting the subject matter of my co-pending application, Serial Number 752,043, filed March 5, 1913, the present case being a division of said co-pending application. 75 In this structure the turret C carries an elongated, substantially horizontally disposed frame E, for which the turret serves as a rotary mounting or support. This frame carries spring mechanism F, which 80 acts upon the end or arms of a trolley fork G in such manner as to yieldingly maintain the trolley pole in engagement with the trolley wire. The trolley pole (not shown) is fastened in the upper end or socket portion H of the fork and usually operates normally at an angle of about forty-five degrees to the horizontal. This trolley fork is pivoted upon a suitable shaft J mounted in bearings on the upper side of the turret 90 C, so that the trolley fork with its pole may swing about its pivot under the influence of the spring mechanism F. The turret also carries a small hook or latch K which, when the trolley fork G and its pole are pulled 95 down into a substantially horizontal position with respect to the top of the car, may be hooked over the edge L of the fork to lock the fork and pole in said horizontal position, this construction being provided to 100 permit the trolley pole to be renewed or replaced in places such as car barns, where the head room is low. I have described these parts generally in order that an understanding may be had of the application of 105 my present invention to a trolley base, but further details of said trolley base may be had by reference to the above mentioned co-pending application.

It will be noted that in the structure 110

shown the parts are all mounted and arranged in such manner that they may swing about the upstanding post or standard B in a substantially horizontal plane, and it will 5 also be noted that these parts in a sense form an operating unit, all supported through the medium of the turret C by the upstanding post or standard B. It often happens that this operating unit becomes 10 damaged to such an extent that it must be removed and replaced by another unit, or other conditions may arise rendering it necessary to remove or replace the operating unit. For these reasons I have constructed 15 and arranged the parts so that the operating units and the base plates, with their upstanding standards, are interchangeable. In other words, each car may be provided with a base plate and standard B, which 20 may be permanently secured in position, these plates being all of a size so that the operating units may be interchangeably mounted in position. In order that the interchanging of the operating units may be 25 quickly and conveniently accomplished under the usual conditions which generally arise in practice, I provide each turret C with a central bolt or member M. This bolt is firmly anchored at its upper end in 30 the top of the turret and it extends downwardly through the hollow post or standard B to a point preferably below the base plate A. The lower end of this bolt is expanded or has a head N, which is adapted to be en- 35 gaged by the forked end O of a locking strip or member P. This locking strip is slidably mounted in a groove in the under side or face of the base plate A, as clearly shown in the drawing, so that it will lie 40 flush with the bottom face of said base plate. The outer end R of this locking strip is upturned to provide a suitable handle for manipulating the strip. It will thus be seen that when the member P is shifted lon- 45 gitudinally so that its forked end O engages the headed end of the central bolt M the turret cannot be lifted off or removed from the standard or post B, but at the same time said locking member does not interfere in 50 any manner with the rotation of the turret and the parts carried thereby. As a safeguard against accidental unlocking movement of this member P I provide a small screw or bolt S, which may be threaded 55 through the plate A and into a suitably threaded hole in the locking member P, thereby holding said member P in its locking position. In order to remove the operating unit, it is simply necessary to unscrew 60 the bolt S, slip the member P until its forked end frees the end of the central bolt M, and the entire operating unit may then be removed from the base plate. It will be noted that the bore of the bolt or standard 65 B, through which the central bolt M ex-

tends, is of sufficient diameter to permit the head N of said bolt to pass through when the pole and operating unit is removed or replaced.

I claim:

1. In a device of the class described, the combination of a base member, a rotary trolley supporting member removably mounted thereon, and a locking device comprising a 70

upstanding turret post, a rotary turret removably mounted on said post, trolley mechanism mounted on said turret and removable therewith as a unit, a headed member carried by said turret and centrally positioned in said hollow post, and a retainer bar slidably mounted in said base, and having a forked end for engaging the headed end of said member to hold said turret in 10 position.

In testimony whereof I have signed my name to this specification, in the presence of two subscribing witnesses, on this 13 day of March A. D. 1914.

CHARLES E. GIERDING.

Witnesses:

W. C. STARKEY,
JNO. L. YOUNG.
